STARTER DRIVE FOR INTERNAL COMBUSTION ENGINES

Youston Sekella, Elmira, N. Y., assignor to Eclipse Machine Company, Elmira, N. Y., a corporation of New York

Application July 31, 1935, Serial No. 34,044

9 Claims.

(Cl. 74—7)

The present invention relates to a starter drive for internal combustion engines and more particularly to gearing for automatically connecting a starting motor to a member of the engine to be started.

It is an object of the present invention to provide a novel starter drive which is simple and economical in construction, small in size and powerful and efficient in operation.

It is another object to provide such a device which includes a novel form of yielding driving connection.

It is a further object to provide such a device which embodies a yielding driving connection including a compression spring in which the spring serves as a keying means for the transmission of torque.

It is another object to provide such a device embodying novel provisions for preventing rebounding of the starting pinion when it is automatically demeshed.

It is another object to provide such a device in which separate compression springs are provided to enforce mesh of the pinion and to form the yielding driving connection.

It is a further object to provide such a device in which the compression spring for enforcing mesh also serves to transmit initial torque.

Further objects and advantages will be apparent from the following description taken in connection with the accompanying drawings in which:

Fig. 1 is a side elevation partly in section of one preferred embodiment of the invention, the device being shown in disengaged position;

Fig. 2 is a sectional view thereof taken substantially on the line 2—2 of Fig. 1;

Fig. 3 is a side elevation of the same rotated through an angle of 90 degrees;

Fig. 4 is a view similar to Fig. 1 showing the device in cranking position;

Fig. 5 is a detail in perspective of a driving disc;

Fig. 6 is a detail in perspective of the compression and torque transmitting spring;

Fig. 7 is a detail in side elevation showing a modified form of compression and drive spring;

Fig. 8 is a side elevation partly in section of a second embodiment of the invention;

Fig. 9 is a view similar to Fig. 8 showing the parts in cranking position;

Fig. 10 is a side elevation thereof partly broken away showing the parts in the positions assumed in case of tooth abutment between the pinion and engine gear;

Fig. 11 is a section taken substantially on the line 11—11 of Fig. 8;

Fig. 12 is a section taken substantially on the line 12—12 of Fig. 8;

Fig. 13 is a detail in perspective of a driven disc and clutch member with the housing and anchoring member for the mesh-enforcing spring, the parts being separated for the sake of clarity;

Fig. 14 is a side elevation partly in section of a further embodiment of the invention, the parts 10 being shown in idle position;

Fig. 15 is a similar view showing the parts in cranking position; and

Fig. 16 is a similar view showing the parts in the positions assumed in case of tooth abutment 15 between the pinion and engine gear.

Referring first to Fig. 1 of the drawings, there is illustrated a starter drive including a power shaft 1 which may be the extended armature shaft of a starting motor not shown. A hollow sleeve 2 is fixed on the power shaft in any suitable manner as by means of a key 3 and set screw 4 and carries freely journalled thereon an actuating member in the form of a screw shaft 5. Longitudinal movement of the screw shaft 5 to the left 25 is limited by a shoulder 6 on the sleeve 2, and movement thereof to the right is limited by an abutment in the form of a stop nut 7 threaded on the end of said sleeve.

An engine driving member in the form of a 30 pinion 8 is freely journalled on the power shaft 1 in position to be moved into and out of engagement with a member such as a flywheel gear 9 of the engine to be started. A nut 11 is threaded on the screw shaft 5 and is splined to the pinion 35 8 for rotation in unison therewith by means of a barrel 12 having slots 13 formed to receive radially extending lugs 14 on said nut. The nut is retained in the barrel by suitable means such as a split ring 15, and the nut and pinion are normally maintained in extended relation by means of a compression spring 16. The nut 11 is normally maintained against the heel 10 of the thread of screw shaft 5 by means of a light compression 40 spring 17 bearing on the stop nut 7, thereby 45 maintaining the pinion 8 in idle position.

A yielding driving connection between the screw shaft 5 and the sleeve 2 is provided in the form of a heavy compression spring 18 formed from radially flattened stock, the end convolutions of which 50 are tapered and provided with flat driving abutments 19, 21 (Fig. 6). Driving and driven discs 22 and 23 respectively are provided which conform to the terminal convolutions of the spring 18 and are provided with shoulders 24 and 25 respectively 55

adapted to engage the abutments 19 and 21 on the spring 18. The driving disc 22 is non-rotatably connected to the sleeve 2 as by a "double D section" indicated at 26 and the driven disc 23 is similarly connected to the screw shaft 5 as indicated at 27 (Fig. 2). It will thus be seen that the spring 18 serves in effect as a spline to connect the screw shaft to the drive shaft 1.

Referring more particularly to Figs. 3 and 4, it will be seen that the groove 28 in the spring 18 which defines the driving abutment 21 is wider than the shoulder 25 of the driven disc 23 so as to provide substantial rotary lost motion between the spring and disc. The longitudinal position of the disc 23 is defined by the shoulder 30 at the end of the threaded portion of the screw shaft, and the parts are preferably so dimensioned that the spring 18 is assembled under initial compression whereby the screw shaft is urged against the abutment 1, and friction between the parts is sufficient to suitably damp such lost motion.

In the operation of this embodiment of the invention, rotation of the power shaft 1 is transmitted through the sleeve 2 and double D section 26 to the driving disc 22. Shoulder 24 on disc 22 thereupon engages the driving abutment 19 on spring 18, causing torque to be transmitted through the spring to the driven disc 23 by engagement of the abutment 21 against the shoulder 25. Rotation of the driven disc 23 is transmitted through the double D section 27 to the screw shaft 5 whereby the nut 11 is traversed along the screw shaft, causing the pinion 8 to mesh with the engine gear 9. When the nut 11 engages the stop nut 7 which defines the meshing position of the pinion 8, the screw shaft 5 is forced back, causing the driven disc 23 to compress spring 18 until sufficient friction is built up in the threads to transmit rotation to the pinion 8 and cause the engine to be cranked. When the engine starts, the overrunning of the pinion 8 causes the nut 11 to be rapidly returned to its idle position against the heel 10 of the thread on the screw shaft, rebounding of the nut being prevented by the damped lost motion of shoulder 25 of driven disc 23 in groove 28 of spring 18.

Should the teeth of the pinion 8 abut against the teeth of the engine gear 9 during the meshing operation, the spring 16 in barrel 12 yields and permits the nut 11 to move forward until sufficient friction is built up in the threads to cause the pinion to be indexed into proper registry, whereupon the spring 16 expands and snaps the pinion into mesh.

The embodiment of the invention illustrated in Figs. 8 to 13 inclusive comprises a power shaft 31 on which is fixed a hollow sleeve 32 by suitable means as indicated at 33. A screw shaft 34 is freely journaled on the sleeve 32, being retained thereon by a stop nut 35 threaded on the end of said sleeve. A pinion 36 is freely journaled on the power shaft 31 in position to be moved into and out of engagement with a member such as a flywheel gear 37 of the engine to be started and is rigidly connected by means of a barrel 38 with a nut 39 threaded on the screw shaft 34.

A driving disc 41 is non-rotatably mounted on the end of sleeve 32 as by means of a double D section indicated at 42 in Fig. 11 and is arranged to receive the terminal convolution of a heavy compression spring 43 and drive the same by means of shoulders 44 (Fig. 9) on the disc, en-

gaging abutment surfaces 45 of the spring. A driven disc and clutch member 46 is provided with shoulders 47 (Fig. 13) adapted to be engaged by abutment surfaces 48 (Fig. 9) of the spring and is mounted on a housing member 49 loosely mounted on shaft 32 and provided with openings 51 (Fig. 13) adapted to receive extensions 52 of the shoulders 47 of discs 46 in order to key the parts together. A comparatively light torsion and compression spring 53 is mounted on sleeve 32 and is provided with an outturned end 54 adapted to be received in an opening 56 in the housing 49. The opposite end of spring 53 is adapted to enter an opening 57 (Fig. 8) in a clutch member 58 suitably fixed on the end of the screw shaft 34, the spring 53 being assembled under sufficient initial compression to yieldingly maintain the screw shaft in its normal position against the stop nut 35.

In the operation of this embodiment of the invention, initial rotation of the power shaft 31 is transmitted through sleeve 32, driving disc 41, spring 43, and driven disc 46 to the housing member 49. Rotation of this housing member is yieldably transmitted by spring 53 to screw shaft 34 which causes the nut 39 to be traversed along the screw shaft until it engages the stop nut 35, thereby causing pinion 36 to move into mesh with engine gear 37. Screw shaft 34 is thereupon forced backward, compressing spring 53 until clutch member 58 engages clutch member 46, whereupon further torque and pressure are transmitted through said clutch members, thus limiting the flexure of the light spring 53. Spring 43 is then compressed and torqued until the pressure and friction built up in the threads of the screw shaft, nut 39 and stop nut 35 becomes sufficient to cooperate with the spring 43 to cause rotation of the pinion 36. When the engine starts, the overrunning of pinion 36 permits the parts to return to their idle positions.

Should the teeth of the pinion 36 abut the teeth of the engine gear 37 during the meshing operation as illustrated in Fig. 10, the light compression spring 53 is compressed until sufficient torque is built up in the threads to index the pinion. When the pinion is thus indexed, the spring 53 expands and snaps it into mesh, whereupon mesh is completed and cranking takes place as usual.

The embodiment of the invention illustrated in Figs. 14, 15 and 16 comprises a power shaft 61 on which is rigidly mounted a sleeve 62 by suitable means as indicated at 63. A screw shaft 64 is loosely journaled on the sleeve 62, being retained thereon by a stop nut 65 threaded on the sleeve and being normally held in engagement with the stop nut by a light compression spring 66.

A nut 67 is threaded on the screw shaft and rigidly connected by a barrel 68 to a pinion 69 which is freely journaled on the power shaft 61 and movable therealong into and out of engagement with a member of the engine to be started such as the flywheel gear 71. The pinion is normally maintained in idle position by means of an antidrift spring 70 mounted on the stop nut 65 and cooperating with the nut 67.

A yielding driving connection between the sleeve 62 and screw shaft 64 is provided comprising a heavy compression spring 72 having tapered terminal convolutions ending in flat abutment surfaces 73 (Fig. 14), and driving and driven discs 74 and 75 suitably splined to the sleeve and screw shaft respectively. The discs 75

are shaped to conform to the end convolutions of spring 72 and are provided with shoulders 76 adapted to cooperate with abutments 73 whereby rotation of disc 74 in the direction of the arrow on shaft 61 is transmitted directly to the spring 72, and from said spring to disc 75, while disc 75 may overrun the spring and the spring may overrun the disc 72. Expansion of spring 72 is preferably limited by a suitable housing 71 enclosing the spring and discs 74 and 75.

In the operation of this embodiment of the invention, rotation of power shaft 61 is transmitted through sleeve 62, driving disc 74, spring 72, and driven disc 75 to the screw shaft 64 which causes traversal of nut 67 into engagement with stop nut 65, thus placing pinion 69 in mesh with engine gear 71. Further rotation of the power shaft causes screw shaft 64 to be forced back, first compressing the light spring 66 until the shoulder 78 at the end of the threaded portion of the screw shaft engages the driven disc 75, whereupon further traversal of the screw shaft is resisted by the compression of the heavy spring 72. When the friction between the threads of the screw shaft and nut has thus been built up sufficiently, the pinion 69 is rotated to crank the engine. When the engine starts, the overrunning of pinion 69 permits the parts to return to idle position, rebounding of the pinion and connected parts toward meshing position being prevented by the overrunning connection 73, 76 between the discs 74 and 75 and spring 72 which permits the screw shaft 64 with its associated parts to continue to rotate until their momentum is dissipated.

In case of tooth abutment between the pinion and engine gear as illustrated in Fig. 16, the light compression spring 66 yields to permit indexing of the pinion whereupon it expands and snaps the pinion into initial mesh, whereupon meshing and cranking take place as usual.

Fig. 7 illustrates a form of yielding driving connection which may be employed in any of the embodiments of the invention described. As there shown, the torsion and compression spring 80 has end convolutions 81 and 82 of less pitch than the body of the spring but of full thickness, terminating in flat abutment surfaces 83 and 84. Driving and driven discs 85 and 86 are provided splined respectively to the sleeve 87 and screw shaft 88, shaped to conform to the end convolutions of the spring and provided with shoulders 89 and 91 adapted to cooperate with the abutments 83 and 84 respectively.

Although certain embodiments of the invention have been shown and described in detail, it will be understood that other embodiments are possible and that various changes may be made in the construction and arrangements of the parts without departing from the spirit of the invention as defined in the claims appended hereto.

What is claimed is:

1. An engine starter drive including a drive shaft, a screw shaft freely journalled thereon, a fixed abutment and a yielding abutment on the drive shaft locating the screw shaft thereon, a nut threaded on the screw shaft and confined thereon by said abutments, an engine driving member, and means for actuating the same from said nut, said yielding abutment including means for providing a lost motion rotary connection between the drive shaft and screw shaft, and being assembled under pressure for frictionally damping said lost motion.

2. In an engine starter drive, a drive shaft, a screw shaft rotatably and slidably mounted thereon, a nut threaded on the screw shaft, an engine driving member on the drive shaft, means connecting the nut and engine driving member for rotation and longitudinal movement in unison, a fixed abutment on said drive shaft for the screw shaft and said nut, a light spring and a heavy spring for opposing longitudinal movement of the screw shaft away from its abutment, and means for connecting the heavy spring directly to the screw shaft after a predetermined compression of the light spring.

3. In an engine starter drive, a drive shaft, a screw shaft rotatably and slidably mounted thereon, a nut threaded on the screw shaft, an engine driving member on the drive shaft, means connecting the nut and engine driving member for rotation and longitudinal movement in unison, a fixed abutment on said drive shaft defining the normal position of the screw shaft and the operative position of said nut, a light compression spring and a heavy compression spring in series urging the screw shaft against its abutment and transmitting rotation thereto from the drive shaft, and means for clutching the heavy spring directly to the screw shaft after a predetermined compression of the light spring.

4. In an engine starter drive, a compression spring formed of flattened wire having square ends, a longitudinally fixed driving disc and a longitudinally movable driven disc having shoulders adapted to cooperate with said square ends for transmission of torque, a screw shaft splined to the driven disc, a pinion adapted to engage and drive a member of an engine to be started, a nut threaded on the screw shaft, connecting means to actuate the pinion from said nut, means for limiting traversal of the nut and screw shaft away from the driving spring, means for limiting traversal of the screw shaft toward the spring, and yielding means urging the screw shaft away from the spring.

5. An engine starter drive including a drive shaft, a screw shaft freely journalled thereon, a fixed abutment and abutment means on the drive shaft including a compression and torsion spring locating the screw shaft thereon, a nut threaded on the screw shaft and confined thereon by said abutments, an engine driving member, means for actuating the same from said nut, and means operative after a predetermined longitudinal movement of the screw shaft for coupling said spring to transmit rotation from the drive shaft to the screw shaft.

6. In an engine starter drive, a drive shaft, a member freely journalled thereon adapted to engage and drive a member of the engine to be started, an actuating member rotatably and slidably mounted on the drive shaft and having connections with said engine driving member whereby relative rotation causes relative translation thereof, yielding means for opposing longitudinal movement of the actuating member away from the engine member and for torsionally transmitting rotation from the drive shaft to said actuating member, and a stop for limiting longitudinal movement of the actuating member and engine driving member toward the engine member, said connections between the actuating member and engine driving member including a longitudinally slidable connection facilitating proper engagement of said driving member with the engine member.

7. In an engine starter drive, a compression

spring formed of flattened wire having terminal abutments, a longitudinally fixed driving disc and a longitudinally movable driven disc arranged to conform with and compressively support the end convolutions of the spring, and having shoulders adapted to cooperate with said abutments for transmission of torque, a screw shaft slidably splined to the driven disc, a pinion adapted to engage and drive a member of an engine to be started, a nut threaded on the screw shaft, connecting means to actuate the pinion from said nut, and means for limiting traversal of the nut away from the driving disc, so arranged that transmission of cranking torque causes the movable disc to approach the fixed disc and compress the spring therebetween.

8. In an engine starter drive, a drive shaft, a member freely journalled thereon adapted to engage and drive a member of the engine to be started, an actuating member rotatably and slidably mounted on the drive shaft and having connections with said driving member whereby relative rotation causes relative translation thereof, yielding means for lightly cushioning the application of translatory force from the actuating

member to the driving member, yielding means for strongly resisting longitudinal movement of the actuating member away from said engine member, said latter yielding means being arranged to transmit rotation from the driving shaft to the actuating member, a stop for limiting longitudinal movement of the actuating member toward the engine member, and means for limiting the flexure of said first-mentioned yielding means due to obstruction of the translation of the driving member.

9. An engine starter drive including a drive shaft, a screw shaft freely journalled thereon, a fixed abutment and a yielding abutment on the drive shaft locating the screw shaft thereon, a nut on the screw shaft confined thereon by said abutments, an engine driving member, and means for actuating the same from said nut, said yielding abutment including means providing a torsional driving connection between the drive shaft and screw shaft capable of initial slippage, said connection being assembled under pressure to frictionally resist such slippage.

YOUSTON SEKELLA. 25
